UNITED STATES PATENT OFFICE.

GUSTAV B. KEIL, OF ST. JOSEPH, MICHIGAN, ASSIGNOR TO UPTON MACHINE COMPANY, OF ST. JOSEPH, MICHIGAN, A CORPORATION OF MICHIGAN.

AIR GUN.

Application filed April 21, 1921. Serial No. 463,246.

To all whom it may concern:

Be it known that I, GUSTAV B. KEIL, of St. Joseph, Berrien County, Michigan, a citizen of the United States, have invented 5 a certain new and useful Improvement in Air Guns, of which the following is a specification.

This invention relates to air guns in general, but more particularly to those having 10 a plunger rod upon which a compression spring and sliding abutment are mounted.

Generally stated, the object of the invention is to ensure a strong and more satisfactory construction than heretofore, so that 15 the mechanism of the gun will not be as liable to get out of order as heretofore, as will more fully appear.

It is also an object to provide certain details and features of construction tending 20 to increase the general efficiency and the serviceability of an air gun of this particular character.

To these and other useful ends, the invention consists in matters hereinafter set 25 forth and claimed, and shown in the accompanying drawings, in which:

Figure 1 is a longitudinal sectional view 30 of a gun embodying the principles of the invention, showing the mechanism thereof in normal position.

Figure 2 is a similar view showing the mechanism in position to discharge the gun when the trigger is pulled.

Figure 3 is an enlarged plan of the plunger mechanism.

Figure 4 is a side elevation of said mechanism.

Figures 5, 6 and 7 are detail perspective views.

Figure 8 is a cross section on line 8-8 in Figure 4.

Figure 9 is a cross section on line 9-9 in Figure 4.

Figure 10 is a cross section on line 10-10 in Figure 4.

Figure 11 is a cross section on line 11-11 in Figure 4.

Figure 12 is a plan of the sheet metal strip from which the plunger rod is made.

Figure 13 shows the sheet metal blank formed from said strip.

Figure 14 shows the first step in bending the blank to form the tubular cylindrical plunger rod.

Figure 15 shows the next step, and that

Figure 16 is a perspective showing the completed plunger rod.

Figure 17 is a detail plan view, on a larger scale, of the rear end portion of the inner barrel.

Figure 18 is a rear elevation or end view of the sheet metal tubular plunger rod, showing the gun barrel in cross section.

As thus illustrated, the invention comprises a barrel 1 secured to the stock 2 in any suitable manner. The plunger head 3 slides in said barrel and comprises a leather washer 3 on the metal holder 4, the latter having a flange 5 which bears against the back of said washer, and a stud 6 which extends through the center of said washer and is riveted over upon the small metal washer 7, whereby said leather washer 3 is firmly clamped in place on said holder. A pin 8 is inserted through the holder 4 to secure it to the plunger rod.

Said plunger rod comprises a cylindrical body portion 9 having a longitudinal slot 10 in the top and bottom thereof, so that parallel portions 11 are provided to form a guide, these portions 11 providing cylindrical sides for said guide, being sections of the tubular member which forms the rod. The rear end portion of said rod has flat sides 12, with upstanding lugs 13 to engage the top of the barrel, and lower lugs 14 to engage the bottom of the barrel, so that the rear end of the rod held against displacement up or down or laterally in the barrel.

Figure 1 is a longitudinal sectional view of a gun embodying the principles of the invention, showing the mechanism thereof in normal position. This is shown in Figure 8 of the drawings.

Figure 2 is a similar view showing the mechanism in position to discharge the gun when the trigger is pulled.

Figure 3 is an enlarged plan of the plunger mechanism.

Figure 4 is a side elevation of said mechanism.

Figures 5, 6 and 7 are detail perspective views.

Figure 8 is a cross section on line 8-8 in Figure 4.

Figure 9 is a cross section on line 9-9 in Figure 4.

Figure 10 is a cross section on line 10-10 in Figure 4.

Figure 11 is a cross section on line 11-11 in Figure 4.

Figure 12 is a plan of the sheet metal strip from which the plunger rod is made.

Figure 13 shows the sheet metal blank formed from said strip.

Figure 14 shows the first step in bending the blank to form the tubular cylindrical plunger rod.

Figure 15 shows the next step, and that

formed in the manner shown. Holes are punched, as shown, for the pin 8 previously mentioned. The abutment 19 is formed of sheet metal, as shown, and slides in the slot 10 of the rod, being made from the section of sheet metal shown in Figure 5, and is passed through the strip shown in Figure 6, and is finally shaped as shown in Figure 7. Thus the abutment engages only the upper and lower edges of said curved portions 11, as shown in Figure 8, so that these portions 11 are rigid and not laterally flexible.

The action lever 20 is pivoted on the gun at 21 and has a link connection 22 with said abutment, as shown, so that the abutment and rod are pulled back (see dotted lines in Figure 2) when the action lever is swung forward, and the abutment is then pushed forward in the slot 10 when the lever is pulled back into normal position. This compresses the coil spring 23 which is interposed between the head 3 and the abutment 19, inasmuch as the trigger 24 enters the opening 15 in the rear end of the plunger rod, thus holding the plunger in retracted position. When the trigger is pulled, the air is compressed in the chamber 25 and discharged into the inner barrel 26 in the usual and well-known manner, so that the projectile in the barrel 26 is discharged from the gun. The stud 6 is hollow, as shown, to hold the tube 27 which discharges the air into the barrel 26, and which slides in the latter.

As the plunger rod is cylindrical, as explained, it is not liable to buckle or be bent out of shape by the operation of the mechanism, as it has the strength and rigidity, more or less, of a tube throughout its entire length, and this ensures increased rigidity and stiffness for the portions 11 which form the guide for the sliding abutment.

It will be seen that the trigger 24 is formed from sheet metal, blanked out and then stamped or pressed into the desired shape, so that it has two ears which are pivoted upon a transverse pin or pivot 47 inserted through the structure of the gun for this purpose. The guide rod 28 has a head 29 which is pivoted at 30 to the trigger, between the ears of the latter, and which extends into a cavity 31 in the stock of the gun. A coil spring 32 is interposed between the shank formed by the head 29, and the inner end of the cavity 31, whereby this spring is compressed when the trigger is pulled back, and is adapted to hold the trigger in its normal position. This forms a very strong and reliable spring arrangement for the trigger, and insures greater uniformity in the tension and quality of the springs, in the manufacture of the gun, as these coil springs 32 can be made of spring wire in the usual and well-known manner.

The said inner barrel 26 has its inner end

provided with a head 33, having a screw threaded portion 34 which is screwed into a threaded socket or opening in the end of the barrel 1 and a cap or head 35 is secured to the outer end of the barrel 26 to fit within the outer end of the outer barrel 36, which latter extends back over the short barrel 1 and is secured in any suitable manner to the stock 2 of the gun. The head or cap 35 is provided with a slot 37 adapted to register with the loading hole 38 in the barrel 36, when the inner barrel 26 is screwed partially in place, so that the gun can be loaded by insertion of the shot through the hole 38 and the slot 37, thereby to fill the magazine chamber 39, in the usual manner. The inner or true barrel 26 has its rear end portion provided with a sheet metal shot feed 40 for feeding the shot into the opening 41 in the barrel 26, so that the projectiles will be discharged in the usual and well known manner. After the gun is loaded in the manner described, the head or cap 35 is then turned enough to bring the slot 37 out of register with the hole 38, and far enough to tighten the threaded portion 34 in the threaded socket 42, whereby this adjustment not only completes the assembling of the gun, or completes the tightening of the inner barrel 26 in place, but also closes the loading hole 38 to prevent the shot from escaping from the barrel of the gun.

It will be seen that the washer 48 which is interposed between the spring 23 and the abutment 19 can either be rigid with said abutment, or loose, as may be desired, said washer sliding back and forth on the plunger rod with the abutment.

What I claim as my invention is:

1. In an air gun, the combination of a barrel, a plunger head in said barrel, a cylindrically tubular member forming the plunger rod of said head, with a longitudinal guide slot in the top and bottom of said member, forming parallel curved side portions which are channel shaped in cross section and therefore rigid instead of being laterally flexible, said rod being formed from a single blank of sheet metal with its edges bent together in front of said slot, an abutment arranged to slide in said longitudinal slot, so that said abutment is movable back and forth between and in engagement with only the upper and lower edges of the cylindrical sides of said member, a coil spring arranged on said member for compression between said head and said abutment, so that said curved side portions extend within the spring, an action lever, a link connection between said lever and said abutment, and a trigger to catch and hold said plunger rod in retracted position, whereby said lever and abutment are then movable to normal position to force

said abutment forward and thereby compress the spring along the cylindrical sides of said tubular member toward said plunger.

2. A structure as specified in claim 1, 5 the rear end portion of said tubular member having flat sides formed with upper and lower lugs in rear of said curved side portions to engage the barrel.

3. A structure as specified in claim 1, said 10 tubular member having a rear end portion formed with flat sides and top and bottom, and with in-turned lugs to limit the rearward motion of said abutment in said member.

15 4. A structure as specified in claim 1, said member being formed from a sheet metal blank having lugs to engage the top and bottom of said barrel, lugs to limit the rearward movement of said abutment, a transverse portion to engage said trigger, parallel longitudinal portions to form said curved side portions, and a portion for attachment to said plunger head.

5. In an air gun, a plunger rod comprising 20 a sheet metal blank cut and then rolled into shape to form a cylindrically tubular member having a longitudinal guide slot between curved sides which are outwardly convex in cross section and channeled on 25 their inner sides and which are, therefore, rigid instead of being laterally flexible, with the edges of the blank bent together in front of said slot, a coil spring outside of and concentric to said curved sides of the tube, and 30 means slidable on said curved or channeled sides to compress the spring.

6. A structure as specified in claim 5, having a spring on said plunger rod, and 40 means slidable in the slot to compress the spring.

7. A structure as specified in claim 5, said member having a flat sided rear end portion formed with upper and lower lugs in rear of said curved sides to engage the 45 barrel, a trigger, and means integral with said member in rear of said lugs to engage said trigger.

8. In an air gun, a hollow plunger rod, a solid metal portion fastened in the end of 50 said rod, said portion having a flange and a stud at the front end thereof, a plunger head mounted on said stud, and a metal washer on the end of said stud to hold said head against said flange, the end of said stud 55 being riveted over on said washer, and a tube in the stud.

9. In an air gun, the method of making a cylindrical plunger rod therefor from a sheet metal blank, thereby to form channel 60 shaped parallel guides, comprising the forming of the flat blank with parallel portions, with a slot between said portions, bending the blank to cylindrically curve said parallel portions, so that these side portions are re-

duced to channel form and rendered rigid 65 instead of being flat and flexible, and thereafter rolling the blank into tubular form, thereby forming a longitudinal guide between said previously curved parallel portions, so that said slot is formed before 70 the sides are curved, and whereby said parallel curved portions become the cylindrical sides of said guide.

10. In an air gun, the combination of a 75 hollow pivoted trigger, a guide rod formed at its front end with a head extending within said trigger, means providing a cavity in which said rod reciprocates, a compression spring on said rod for compression by 80 said head in said cavity, a plunger rod having a rear integral portion to engage said trigger, a pivot for said trigger above the plane of said integral portion, and a pivot extending through said head and trigger below said integral portion. 85

11. A structure as specified in claim 10, said spring being coiled on said rod and 90 said trigger being of sheet metal with side portions embracing the pivoted end of said rod.

12. In an air gun an inner barrel, means forming a projectile magazine around the inner barrel, a screw connection for the inner end of said barrel, means providing an opening through which the projectiles 95 are allowed to enter the magazine, in loading the gun, and means whereby rotation of said barrel closes said opening without limiting the rotation.

13. A structure as specified in claim 12, 100 said last mentioned means comprising a cylindric portion which is rigid with said barrel and which fits and rotates in the outer end of said projectile magazine and which has an aperture to register with said 105 opening while the gun is being loaded.

14. In an air gun an outer barrel, an inner barrel disposed centrally within the outer barrel, forming a magazine chamber around the inner barrel, the outer barrel 110 having an opening to permit the projectiles to enter the magazine chamber, in loading the gun, the inner barrel having an opening to permit the projectiles to enter from the magazine chamber, with a sheet metal 115 feeding device secured to the inner barrel to direct the projectiles into the opening thereof, a cap fixed on the outer end of the inner barrel to close the outer end of the outer barrel, said cap having a slot to register with the opening through which the projectiles enter the outer barrel, and a screw connection for the inner end of the inner barrel, whereby rotation of the inner barrel 120 serves to close said opening in the outer barrel and screw the inner barrel tightly in place. 125

GUSTAV B. KEIL.
